[57] CLAIM

The ornamental design for an umbrella handle, as shown and described.

DESCRIPTION

FIG. 1 is a perspective view of an umbrella handle showing our new design, the umbrella shown in broken line for illustrative purposes only;

FIG. 2 is a top plan view thereof;

FIG. 3 is a rear elevational view thereof, the handle loop shown in an open position;

FIG. 4 is a side elevational view thereof;

FIG. 5 is a front elevational view thereof;

FIG. 6 is a bottom plan view thereof; and

FIG. 7 is a perspective view thereof from the bottom, showing the loop in a closed position.
